UNITED STATES PATENT OFFICE.

OSCAR T. SUNDIN, OF PROVIDENCE, RHODE ISLAND, ASSIGNOR TO DAVID H. ZELL, INCORPORATED, A CORPORATION OF NEW YORK.

ARTICLE HOLDER.

Application filed July 25, 1922. Serial No. 577,317.

To all whom it may concern:

Be it known that I, OSCAR T. SUNDIN, citizen of the United States, residing at Providence, in the county of Providence and State of Rhode Island, have invented certain new and useful Improvements in Article Holders, of which the following is a specification.

My invention relates to a holder adapted for retaining articles such as memorandum pads, check books, match books, and the like.

The essential objects of my invention are to enable the substitution or renewal of the article in the holder at will; to render initial binding of the articles unnecessary; to insure against accidental escape of the article from the holder; to facilitate insertion of the article therein; and to attain these objects in a simple and inexpensive structure.

To the above ends essentially my invention consists in such parts and in such combinations of parts as fall within the scope of the appended claims.

In the accompanying drawings which form a part of this specification,

Figure 1 is a perspective view of my holder in closed position engaging a book of paper matches,

Figure 2, a similar enlarged view of the same open,

Figure 3, a section of the same on line 3-3 of Figure 1,

Figure 4, a section of the holder on line 4-4 of Figure 3, and

Figure 5, a perspective view of the clamping member.

Like reference characters indicate like parts throughout the views.

In the form of my invention herein illustrated a flexible casing is provided comprising a backing portion 8, a short flap portion 9, and a longer flap portion 10. The casing may be of leather or other tough protective flexible material which will facilitate bending or folding at the bases of the flaps, as at 11 and 12. The flaps overlap and are engageable with each other to form a front wall by means of a separable or snap fastener 14 in the flap margins.

A metallic clamp or clip member cut and shaped by suitable tools from a single sheet of metal comprises an oblong plate or base

16 with end folds 17 forming inturned ears 18 terminating in inturned prongs 19. Integral with one side of the base is a back wall 20 provided with a resilient inturned flange 21 substantially parallel with the base. Formed in an intermediate portion of the forward edge of the flange is a downwardly directed lip 23. There are unbent flat portions 24 of the flange 21 at each side of the lip.

The described member is permanently engaged with the casing as follows. The base or strip 16 rests transversely of the latter upon the inner face of the back 8 adjacent the foldable portion 11 of the flap 70 9. The originally unbent ends 18 of the base strip are inwardly bent around the lateral edges of the casing so that the resultant ears or lugs bear against the outer face of the back 8 at its lateral margins, 75 with the prongs 19 embedded in the casing, as shown in Figure 4. It will be noted that not only is the metallic member a single integral piece but that it is engageable with the casing with speed and facility. 80

The article to be carried in the holder does not require to have affixed thereto any auxiliary attaching means, and is insertable solely from either side edgewise of the casing. In this instance the article is a match book comprising the matches 25, abrasive binding strip 26, staple 27, and cover 30. The portion 26 of the book is slid edgewise into the clamp from either side, being guided in its travel over the base 16 by 85 the flat guide portions 24 pressing downwardly from above. When the book reaches the depending lip 23 the pressure of the lip upon the book increases as greater stress is exerted on the resilient flange 21, and thus 90 the book is tightly clamped after its complete insertion.

I claim:

1. In a device of the character described, the combination with a flexible casing, of a flat metallic base strip disposed transversely upon an intermediate portion of the casing, folded lugs on the ends of the strip embracing the lateral edges of the casing, an upright back upon the strip, an overhanging flange on the back, and a depending lip on the flange.

2. In a device of the character described the combination with a flexible casing of a flat metallic base strip resting on the in-

ner face of an intermediate portion of the casing, inwardly folded lugs integral with the ends of the strip embracing the lateral edges of the casing and resting against the outer face of the casing, inwardly directed prongs on the lugs embedded in the casing, a back integral with the strip, a flange

on the back above the strip, and a downwardly directed lip formed in the forward edge of the flange.

In testimony whereof I have affixed my signature.

OSCAR T. SUNDIN.
